UNITED STATES PATENT OFFICE.

WILLARD J. FERRIS, OF JACKSON, MICHIGAN, ASSIGNOR TO REYNOLDS SPRING COMPANY, OF JACKSON, MICHIGAN.

DUPLEX RECEPTACLE.

Application filed October 6, 1928. Serial No. 310,785.

The invention relates to a duplex receptacle.

The object of the present invention is to provide a simple, practical and efficient duplex receptacle of strong and durable construction, adapted to be easily and cheaply manufactured, and equipped with polarity slots and having spaced bus bars completely insulated from each other so that there will be no liability of arcing or accidental short-circuiting.

With these and other objects in view, the invention consists in the construction and novel combination and arrangement of parts hereinafter fully described, illustrated in the accompanying drawings, and set forth in the claims hereto appended, it being understood that various changes in the form, proportion, and minor details of construction, within the scope of the claims, may be resorted to without departing from the spirit of the invention or sacrificing any of the advantages thereof.

In the drawings:

Fig. 1 is a front elevation of a duplex receptacle constructed in accordance with this invention.

Fig. 2 is a rear elevation of the same.

Fig. 3 is a similar view, the detachable cover plate being removed to illustrate the arrangement of the bus bars.

Fig. 4 is a rear elevation of the body, the bus bars and the detachable cover plate being removed.

Fig. 5 is a side elevation of the duplex receptacle.

Fig. 6 is a longitudinal sectional view taken on the line 6—6 of Fig. 3.

Fig. 7 is a transverse sectional view on the line 7—7 of Fig. 6.

Fig. 8 is a transverse sectional view on the line 8—8 of Fig. 6.

Fig. 9 is a detail perspective view of one of the bus bars.

In the accompanying drawings, in which is illustrated the preferred embodiment of the invention, the duplex receptacle comprises in its construction a body constructed of molded bakelite or other suitable insulating material and consisting of a relatively thin face plate 1 provided at its rear face with transversely disposed substantially oblong blocks 2 formed integral with the face plate.

The oblong blocks 2 are spaced apart and

are connected by a central longitudinal web 3 forming a partition and cooperating with the transversely disposed blocks to form side recesses 4 to receive terminal arms 5 and line wire attaching means of bus bars 6, which have the said line wire attaching means spaced apart and separated by insulating means so that there is no danger of short-circuiting or arcing. The face plate is provided with an inclined marginal flange 7 to form a beveled edge, and it is reinforced by central longitudinal ribs 8 and transverse ribs 9 which extend from the transverse blocks 2 to the marginal flanges. The longitudinal ribs are arranged in alignment with each other and with the central web 3, and extend from the sides of the transverse blocks, and the transverse ribs 9 extend from the ends of the transverse blocks to the said marginal flanges.

The face plate is provided at its inner or rear face with a central rectangular enlargement 10 forming a base and provided with spaced longitudinal flanges 11 arranged in pairs and arranged centrally of the side recesses 4 in spaced relation with the central web 3, and the transverse blocks 2, and adapted to receive the ends of the terminal arms 5 to support the same and prevent the said arms 5 from being bent inwardly by the operator in attaching the line wires or circuit wires to the bus bars, and they also prevent any strain on the said wires from bending the arms 5 outwardly from their proper position in the side recesses 4.

The face plate is provided with slots 12 and 13 arranged in pairs at the upper and lower portions of the face plate, the slot 13 of each pair being longer than the slot 12 to polarize the device, and the said face plate is beveled at the marginal edges of the slots to facilitate the introduction of the knife blades of a plug, which knife blades are designed to be of different sizes to cooperate with the slots 12 and 13. The transverse blocks are provided with spaced openings 14 forming chambers which communicate with the slots 12 and 13 and which are adapted to receive spring fingers 15 of the bus bars 6. The transverse blocks form housings for the spring fingers of the bus bars, and the inner side walls of the openings 14 are notched at 16 to receive the bus bars and to permit the same to be arranged with their rear faces in flush relation with seats formed by recessing the 110

rear faces of the blocks to provide marginal flanges 17 which are arranged at the ends and outer sides of the said blocks to fit against the sides and ends of a removable cover plate 18.

- 5 The cover plate 18, which is rectangular, covers and conceals the bus bars, and protects the same, and its end portions fit snugly within the marginal flanges 17 of the transverse blocks. The cover plate is secured in 10 place by suitable fastening devices which may, as clearly illustrated in Fig. 7 of the drawings, consist of screws 19 embedded in the central portions of the transverse blocks and having projecting threaded portions 20 15 piercing the cover plate 18 and receiving nuts 21 for clamping the cover plate against the plugs.

The bus bars 6 consist of thin strips of suitable conducting metal provided at their ends 20 with the spring fingers 15 formed integral with the bus bars and having terminal portions 22 bent in opposite directions at an obtuse angle to form a flaring entrance to permit the knife blades to be readily inserted 25 between the spring fingers, and one or both of the spring fingers are preferably provided with an indentation 23 forming a protuberance at the inner face of the spring finger to insure proper contact between the knife 30 blades and the spring fingers. The bus bars are located at opposite sides of the central partition 3 and in spaced relation with each other and with the partition, and the arms 5, which are formed integral with the bus bars, 35 extend from the same centrally with the outer edges thereof, as clearly illustrated in Fig. 8 of the drawings. The bus bars are firmly retained in position by the cover plate, and the arms 5 are recessed at their side edges 40 at 24 to form opposite shoulders and to receive tongues 25 of a contact plate 26. The tongues 25 are arranged in pairs and are bent around the recessed edges of the arms 5 to receive the shoulders formed by the 45 recesses for gripping the contact plates to the arms. The contact plate 26 is pierced by a binding screw 27, which is threaded into the contact plate. The ends of the contact plate are slit at spaced points to form the tongues 50 25, and at intermediate portions of the metal of the contact plate between the tongues 25 are bent outwardly to form projections 28 which cooperate with the binding screw in holding the bad portion of a wire. The bus 55 bars are identical in construction and are reversible and either bus bar may be arranged in position at either side of the central partition, so that the parts of the duplex receptacle may be easily and quickly assembled.

60 The cover plate may be of any suitable insulating material, and fits snugly in position, and is firmly secured in place. The face plate is provided with suitable apertures for the reception of fastening devices for securing it 65 in position.

What is claimed is:

1. A duplex receptacle comprising a body of insulating material consisting of a face plate provided at the rear face with integral spaced transverse blocks and a central longitudinal web forming a partition and cooperating with the blocks to provide side recesses, said blocks having spaced openings communicating with slots in the face plate, and spaced bus bars located at opposite sides of the central partition and provided at their ends with spring tongues located in the openings of the transverse blocks, said bus bars being also provided with arms located in the said side recesses and provided with wire attaching means. 70

2. A duplex receptacle comprising a body of insulating material consisting of a face plate provided at the rear face with integral spaced transverse blocks and a central longitudinal web forming a partition and cooperating with the blocks to provide side recesses, said blocks having spaced openings communicating with slots in the face plate, spaced bus bars located at opposite sides of the central partition and provided at their ends with spring tongues located in the openings of the transverse blocks, said bus bars being also provided with arms located in the 75 said side recesses and provided with wire attaching means. 80

3. A duplex receptacle comprising a body of insulating material consisting of a face plate provided at the rear face with integral spaced transverse blocks and a central longitudinal web forming a partition and cooperating with the blocks to provide side recesses, said blocks having spaced openings communicating with slots in the face plate, and spaced bus bars located at opposite sides of the central partition and provided at their ends with spring tongues located in the openings of the transverse blocks, said bus bars being also provided with arms located in the 85 said side recesses and provided with wire attaching means, a cover plate of insulating material fitted over the bus bars, and marginal flanges formed at the rear faces of the transverse blocks and extending around the end portions of the cover plate and fitting the 90 same. 95

3. A duplex receptacle comprising a body of insulating material consisting of a face plate provided at the rear face with integral spaced transverse blocks and a central longitudinal web forming a partition and cooperating with the blocks to provide side recesses, said blocks having spaced openings communicating with slots in the face plate, and spaced bus bars located at opposite sides of the central partition and provided at their ends with spring tongues located in the openings of the transverse blocks, said bus bars being also provided with arms located in the 100 said side recesses and provided with wire attaching means, and spaced flanges carried by the face plate and arranged at the inner and outer sides of the said arms for holding the same against inward and outward movement. 110

4. A duplex receptacle comprising a body of insulating material consisting of a face plate provided at the rear face with integral spaced transverse blocks and a central longitudinal web forming a partition and cooperating with the blocks to provide side recesses, said blocks having spaced openings communicating with slots in the face plate, spaced bus bars arranged at opposite sides of the said partition and provided at their ends 120 125 130

with spring fingers located in the said openings, said bus bars being provided with central arms arranged in the side recesses, contact plates fitted against the arms and provided with spaced tongues embracing the arms and interlocked with the same, and binding screws carried by the contact plates.

5. A duplex receptacle comprising a body of insulating material consisting of a face 10 plate provided at the rear face with integral spaced transverse blocks and a central longitudinal web forming a partition and cooperating with the blocks to provide side recesses, said blocks having spaced openings communicating with slots in the face plate, spaced bus bars arranged at opposite sides of the said partition and provided at their ends with spring fingers located in the said openings, said bus bars being provided with central 15 arms arranged in the side recesses, contact plates fitted against the arms and provided with spaced tongues embracing the arms and interlocked with the same, said contact plates being also provided with projections located 20 between the arms and extending outwardly, and binding screws carried by the contact plates and located between the said projections.

6. A duplex receptacle of insulating material consisting of a face plate having a central enlargement forming a base and provided at the ends thereof with spaced transverse blocks having spaced openings, said blocks being recessed at the inner side walls of the openings and provided at the outer 30 sides and ends with marginal flanges forming seats, and a central longitudinal web connecting the transverse blocks and cooperating therewith to provide side recesses, spaced bus bars fitted in the notched portions of the 35 transverse blocks and provided at their ends with spring arms arranged in the said openings, said bus bars being provided with arms extending into the side recesses, spaced flanges carried by the base and arranged at the inner 40 and outer faces of the said arms and holding the same against inward and outward movement, wire attaching means carried by the said arms, and a removable cover plate secured to the blocks and arranged within the 45 marginal flanges thereof and covering the bus bars.

In testimony whereof I have hereunto set my hand this 2nd day of October, 1928.

WILLARD J. FERRIS.
